Byron H. Lengsfield

By Maev Fennick Lawrence,
Attorney

UNITED STATES PATENT OFFICE.

BYRON H. LENGSFIELD, OF NEW ORLEANS, LOUISIANA.

CANDY BOX.

Application filed June 25, 1925. Serial No. 39,567.

To all whom it may concern:

Be it known that I, BYRON H. LENGSFIELD, a citizen of the United States, residing at New Orleans, in the parish of Orleans and 5 State of Louisiana, have invented certain new and useful Improvements in Candy Boxes; and I do hereby declare the following to be a full, clear, and exact description of the invention, such as will enable others 10 skilled in the art to which it appertains to make and use the same.

This invention relates to improvements in the manufacture of paper boxes, and more particularly to the construction of a box top, 15 made to provide a means for receiving descriptive or decorative cards for designating different seasons and occasions, and as holidays and the like.

An object of this invention is to provide 20 a box-top constructed in a manner adapted to receive descriptive or decorative cards, as for instance, when a holiday has just passed, and a dealer has a considerable stock of packages provided with these tops, he may, 25 by merely withdrawing the cards, have the usual staple package of the manufacture immediately ready for sale without any loss or delay whatever.

A further object of this invention is to 30 provide a construction for a box cover that will freely and positively allow descriptive or decorative cards to be inserted therein or removed therefrom. Paper boxes now in use having tops designed to carry cards are 35 inefficient owing to the fact that the cards are not easily inserted or removed, the guiding edges of the pocket for the cards are invariably obstructed by particles of hardened glue or the like, and one of the prime 40 objects of this invention is to eliminate this serious difficulty.

In the drawings,

Fig. 1. illustrates a perspective view of the container showing the top sections in un-assembled form slightly raised from the main body portion of the top and in their proper relative vertical position thereto.

Fig. 2. represents a perspective view of the container with the top section raised and 50 detached from two side edges.

Fig. 3. represents a sectional elevation view of the container, with top section raised on one edge.

Fig. 4. illustrates a plan view spread out of the covering for the top edges, sides and 55 ends of the main body portions of the container.

Numerical 1, designates the main body member of the container having four sides and bottom while the top or cover portion 60 is adapted to slide in telescopic relation thereto, and is composed of a main frame 2, comprising four sides, and a top section 3. A layer 4 of suitable material, preferably 65 paper, is adapted to be stretched over frame 2 and 3, and properly glued or otherwise thereto. The layer 4 is primarily shaped from a section of material approximately as disclosed in Fig. 4 having overlapping portions 5 for fitting in around the edges of 70 the frame 2 and 3, the panel 6 of layer 4, may be suitably supplied with illustrations, printed matter or otherwise as at 7, 8 or 9. A frame section 10 of cardboard or other 75 suitable material, is adapted to be integrally attached to the top section 3 and 4, along three edges thereof, by means of a paper covering or other material for the frame 10, the frame covering being cut into proper form for overlapping three edges of the top 80 portion 3 and 4, as at 11, 12 and 13, the corresponding overlapping portion 14 is adapted to be folded over one outside edge 85 of the frame as at 15, the inside edges of the frame covering are formed to allow overlaps as at 16, 17, 18 and 19, these overlaps being approximately the width of the side portions of the frame, which may be shaped in any suitable form. On securely fastening the overlapping portions of the frame 90 covering to their respective sections by means of glue or otherwise, a top or cover portion is formed having a pocket adapted to efficiently and with negligible friction receive a card 20. The pocket being formed 95 by securely fastening three outside edges of the frame 10 to the top cover portions 3 and 4, by means of overlaps 11, 12 and 13 of the covering material for the frame, the overlaps 16, 17, 18 and 19 are folded underneath the inside edges of frame 10 and extending approximately the width of the frame sections, thereby allowing the card to be easily slipped into and out of the pocket without danger of contacting with 100 hardened portions of glue or fastening.

105

material that might, as in other constructions, lodge in the guides. The efficiency of the pocket entrance is greatly enhanced by the folding under and fastening of the overlap 14 to entering edge 15 of the frame 10.

In operation the box, container or package may be filled with gift articles, or otherwise, and the cover or lid adapted to contain suitable information to indicate the nature of 10 the gift articles the cover being provided with a pocket having an open face and a removable card in the pocket containing information relative to some special occasion, the card when in place covering the above 15 suitable information whereby the package may be sold as a gift package with reference to the special occasion with the card in place, and whereby the package may be sold as a standard staple package when the card 20 is removed.

What I claim is:

1. A box cover having side walls, end walls and a top, an open faced frame adapted to receive a card superimposed on the top, 25 means for fastening the frame to the top along two side edges and one end thereby forming a pocket having an entrance at the open end, the means consisting of suitable covering material for the frame, cut to allow for overlap along the outside and inside edges of the frame, the outside overlaps being adapted for securely fastening three 30 outside edges of the frame to the corresponding edges of the box cover.
2. A box cover having side walls, end walls and a top, an open faced frame adapted to receive a card superimposed on the top, means for fastening the frame to the top along two side edges and one end thereby 35 forming a pocket having an entrance at the open end, the means consisting of suitable covering material for the frame cut to allow for overlap along the outside and inside edges of the frame, the outside overlaps being adapted for securely fastening three 40 outside edges of the frame to the corresponding edges of the box cover, the remaining outside edges of the frame being adapted for securely fastening three 45 outside edges of the frame to the corresponding edges of the box cover, the remaining outside flap being turned and fastened over the edge of the frame at the entrance to the pocket, thereby forming a finished

entrance to the pocket, thereby forming a 50 finished pocket opening.

3. A box cover having side walls, end walls and a top, an open faced frame adapted to receive a card superimposed on the top, means for fastening the frame to the top along two side edges and one end thereby 55 forming a pocket having an entrance at the open end, the means consisting of suitable covering material for the frame cut to allow for overlap along the outside and inside edges of the frame, the outside overlaps being adapted for securely fastening three 60 outside edges of the frame to the corresponding edges of the box cover, the remaining outside flap being turned and fastened over the edge of the frame at the entrance to the pocket, thereby forming a finished 65 pocket opening, the overlaps at the inside edges of the frame being approximately the width of the frame sections, 70 thereby allowing a maximum fastening surface and assuring the minimum amount of friction in inserting and removing the card from the pocket.

4. A box cover having side walls, end 75 walls and a top, an open faced frame adapted to receive a card superimposed on the top, means for fastening the frame to the top along two side edges and one end thereby forming a pocket having an entrance at 80 the open end, the means consisting of suitable covering material for the frame cut to allow for overlap along the outside and inside edges of the frame, the outside overlaps being adapted for securely fastening three 85 outside edges of the frame to the corresponding edges of the box cover, the remaining outside flap being turned and fastened over the edge of the frame at the entrance to the pocket, thereby forming a finished 90 pocket opening, means for forming side guides for the card free from obstruction caused by particles of box glue, consisting of the overlaps along the under inside edges of the frame being approximately the width 95 of the frame section.

In testimony whereof I affix my signature.
BYRON H. LENGSFIELD.
